[57] **CLAIM**

The ornamental design for an element for a noise cancellation device, as shown and described.

DESCRIPTION

FIG. 1 is a perspective view as seen from the upper front of an element for a noise cancellation device showing our new design;

FIG. 2 is a top plan view thereof;

FIG. 3 is a bottom plan view thereof; and,

FIG. 4 is a front elevational view wherein the right side, left side and rear are substantially identical.
